UNITED STATES PATENT OFFICE.

ROGER HARRY DAVID, OF ST. PAUL, MINNESOTA.

DOUBLE-POINTED PUSHPIN.

1,413,833.

Specification of Letters Patent. Patented Apr. 25, 1922.

Application filed January 19, 1920. Serial No. 352,414.

To all whom it may concern:

Be it known that I, ROGER HARRY DAVID, a citizen of the United States, residing at St. Paul, in the county of Ramsey and State of Minnesota, have invented a new and useful Double-Pointed Pushpin, of which the following is a specification.

My invention relates to improvements in double pointed push pins.

10 Its object is to provide a simple, durable and inexpensive device of this kind adapted to firmly support objects upon a wall or other structure.

A further object is to supply a device of this nature, which may be readily applied to and detached from various objects to be supported and being further adapted to be easily applied to and removed from carrying structures.

20 With the foregoing and other objects in view, which will appear in the following description, the invention resides in the novel combination and arrangement of parts and in the details of construction hereinafter described and claimed.

In the drawings, Figs. 1 and 2 are side elevations of my improved device. Fig. 1 shows the improvement as employed in supporting a picture upon a wall and Fig. 2 shows the same in position upon a wall to receive draperies or the like. Fig. 3 is an elevation at right angles with respect to Fig. 1; Fig. 4 is an end view of the device and Fig. 5 is an enlarged perspective view thereof.

35 In the drawings, I have illustrated a device embodying my invention and comprising a body 10 having a pin 11 passing therethrough and projecting from either side thereof, the extremities of said pin being pointed as at 12. The body 10 may be of glass or other suitable material and is sealed or otherwise fixed upon the pin 11 in any manner desired. Said body 10 is preferably cone-like in form, as illustrated in the drawings and may be easily grasped in the fingers of the user. A flat bearing or bracing surface 13 at the base of the body has the general form of an ellipse. One end of the pin 11 projects from the center of this sur-

50 face and extends at right angles with respect to the minor axis thereof, but forms an acute and an obtuse angle (substantially forty five and one hundred and thirty five degrees)

with respect to the major axis of said surface.

55

My device is particularly adapted to support pictures of the smaller variety. In use, the body 10 is grasped between the fingers of the user, the end of the pin 11 projecting from the bearing surface 13 of the body being pressed in a vertical plane, obliquely upward, its entire length into the frame of a picture (Fig. 1), thus bringing said bearing surface into contact with said frame. The body 10 then serves to reinforce the pin 65 against displacement and rigidly braces the pin in a vertically inclined position. The picture is hung upon a wall or other support by bearing inwardly and downwardly upon the frame, thus pressing the lower end of the 70 pin into the support. The inclined position of the pin is maintained by engagement of the bearing surface 13 with the picture frame and the weight of the picture, when released, tends to continually and more firmly imbed 75 the lower end of the pin into the support. To remove the picture, the frame is lifted to withdraw the pin 11 from the wall. The body 10 may be, thereafter, readily grasped and the pin removed from the frame. In 80 hanging pictures or the like, my device may be used singly or in pairs, as desired. One of the alternate uses of my device is for supporting draperies or the like. The device in this instance is reversed as above described, 85 the end of the pin 11 projecting from the bearing surface 13 of the body 10 being pressed obliquely downward into the wall or other support, so as to bring said surface into contact therewith (Fig. 2). The opposite end of the pin 11 is then held in upwardly inclined position and readily receives and firmly supports a drape or the like, the point of the pin 11, if visible, being hardly discernible, while the body 10 is completely concealed from view.

90

95

In manufacturing my device, the body 10 is preferably molded about the pin 11 and thereby sealed or fixed thereto. The application of the body to the pin, however, may 100 be accomplished in other ways.

Changes in the specific form of my invention, as herein disclosed, may be made within the scope of what is claimed without departing from the spirit of my invention.

105

Having described my invention, what I

claim as new and desire to protect by Letters Patent is:

In a device of the class described, a cone-like body and aligned pointed projections extending from the apex and the base of said body, said base being formed in oblique relation with respect to the axes of said projections and providing a bearing or bracing

surface adapted to rest against an upright support or against an object to be supported, the vertical dimension of said surface being greater than the transverse dimension thereof.

In testimony whereof, I have signed my name to this specification.

ROGER HARRY DAVID.
